UNITED STATES PATENT OFFICE.

WILLIAM F. KIESEL, JR., OF ALTOONA, PENNSYLVANIA.

COMPARTMENT FREIGHT CAR.

Application filed April 12, 1928. Serial No. 269,537.

This invention relates to freight cars and more particularly to that type of freight car which is adapted to carry a plurality of separate individually removable freight compartments. The invention is more especially directed to means for retaining such compartments in position on flat cars in such a manner that the doors to the compartments may be opened without removing them from the car.

It is therefore a general object of the present invention to provide a novel and improved freight car.

More particularly it is an object of the invention to provide corner stops for freight car compartments, that cooperate with the compartments in such a manner as to allow their doors to be opened without removing the compartments from the car.

One of the features of the invention consists in forming a compartment stop in such a manner as to provide two pockets for the corners of adjacent compartments and to form integral with the stop fitting a collar-like portion providing a stake pocket.

Another feature of the invention comprises the arrangement of a freight car of the flat type, adapted to carry freight compartments, with a plurality of stake pocket fittings secured to each side sill, those fittings arranged between the ends of independently removable freight compartments being below the floor of the car, while those in line with the ends of adjacent compartments project above the floor of the car and are provided with pockets to engage with the corners of the two adjacent compartments.

Other and further features and objects of the invention will be more apparent to those skilled in the art upon a consideration of the accompanying drawings and following specification wherein is disclosed a single exemplary embodiment of the invention, with the understanding, however, that various changes may be made therein such as fall within the scope of the appended claims without departing from the spirit of the invention.

In said drawings:

Figure 1 is a side elevation of a freight car constructed according to the present invention and equipped with removable freight compartments;

Figure 2 is an end elevation of the car and a compartment thereon;

Figure 3 is a partial horizontal section taken on line 3-3 of Fig. 1 and looking downward;

Figure 4 is an elevation, on a larger scale, of the combined compartment stop and stake pocket fitting;

Figure 5 is a vertical section on an enlarged scale taken on line 5-5 of Fig. 1 and showing the stake pocket and stop fitting in elevation; and

Figure 6 is a vertical section on line 6-6 of Fig. 4.

It is well-known in the art to provide a plurality of freight compartments, a number of which may be mounted on or carried by a suitable freight car, so that partial car shipments may be facilitated. Heretofore elaborate means have been provided for retaining the compartments in position, often combining locking or hooking means, all of which add to the complication of the construction and offer difficulties in the application of the system. The present invention comprises an extremely simple method of attaching the compartments and at the same time allows the use of the car for its ordinary purpose without any change.

Referring to the drawings, there is disclosed at C a flat car which may be of conventional type and provided with the side sills 10 formed as shown substantially as a beam of constant strength, although obviously any type of side sill may be used.

The car is adapted to carry a plurality (here shown as five) of compartments 11 which may be of conventional form. As shown, they are substantially of rectangular configuration in both plan and elevation, having, however, the slightly rounded roof parts 12. As shown, the ends of these compartments which face each other when the compartments are in position on the car as shown, are of corrugated metal 13 for added strength. The compartments may be provided with suitable rings 14 for the attachment of lifting slings. Each compartment as shown, is of substantially the same width as the floor 15 of the car and the car is of such length as to just accommodate the desired number of compartments.

Each compartment is provided in one of its side walls, i. e., one of the walls facing the side of the car when positioned as shown, with a suitable door or doors 16 which preferably is hinged at one vertical edge and swings outwardly, being held closed by any

suitable latch means 17 as shown, which may be adapted to be locked or sealed as desired.

The customary flat car is provided with 5 stake pocket fittings such as 18, shown secured to the vertical face of the side sill. These fittings are conveniently spaced from two and one-half to four and one-half feet apart on the standard freight cars and are 10 each provided with a vertical sleeve or collar adapted to receive the end of the stake which may be driven therein to retain certain types of loads, i. e., lumber, iron bars and the like, in position on the car. In 15 order to adapt such a flat car for carrying freight compartments, some of the usual stake pockets may conveniently be retained and moved if required to be positioned say midway of the length of each compartment, 20 as shown in Fig. 1. These stake pocket fittings do not project above the floor of the car and therefore do not interfere with opening the compartment doors. It will often be found convenient to open these 25 doors for loading or unloading the compartments without removing them from the car.

The compartments are normally spaced apart a slight distance from each other as 30 shown at 19. They are held in this position and also from movement laterally or longitudinally of the car by the combined compartment stop and stake pocket fitting generally indicated at 20, there being one 35 of these arranged at the outer end of each end compartment and one between each two compartments on each side sill as shown. Figs. 3 to 6 show in detail the construction of this combined stop and stake pocket fitting. It is preferably a casting of malleable iron. It comprises essentially a plate 21 adapted to fit against and be riveted or otherwise secured to the vertical web 22 of the side sill 10 as shown in Fig. 5. For 40 the sake of rigidity, the portions 23 of this plate are formed as slightly elevated ribs and only the portions 24 fit against the sill web. These portions 24 are drilled as shown to receive suitable fastening means. 45 Extending laterally from the upper edge of this plate 21 is the plate 25 adapted to rest on top of the flange 26 of the side sill when the fitting is in position as shown in Fig. 5.

Formed integral with the plate 25 and extending upwardly therefrom is the spacer block 27 substantially rectangular in horizontal section and preferably hollow as 50 shown in Fig. 6 for the sake of lightness. The top of this block is chamfered in four 55 directions as best shown in Fig. 3, wherein the sloping faces 28 and 28' are the larger and face toward the front and rear of the car respectively, and the smaller faces 29 and 29' face toward the center and away 60 from the car respectively. The outer wall 65

30 of this block is a substantial continuation of the plate 21. Extending from this wall 30 and upwardly from the plate 21 are the wings 31. They extend to the full width of the plate 21 and at least to the full height 70 of the spacer block as shown in Fig. 4. The upper edges of these wings are turned outwardly as best shown in Figs. 5 and 6 at 32.

The block is braced from the plate 21 by 75 means of the integral webs 33 substantially vertical and extending at right angles to the plate 21, they being really extensions of the side walls 34 of the block at the junctions of the wings therewith. These webs 33 are 80 widest at the top and taper down until they almost merge into the plate 21 at the bottom. The wide portions 35 of these webs are connected together at their outer edges by means of the plate 36 to thus form a collar 85 or ring-like member having as side walls the web portions 35, as the outer wall the plate 36, and as the inner wall the wall 30 of the spacer block. They thus form a vertical passageway or stake pocket of the proper size 90 and configuration to receive the usual vertical stake as used on freight cars. The upper and lower edges of the stake pocket may be reinforced by suitable flanges as shown at 95 37 and 38 respectively which flanges suitably merge into other parts of the structure at their ends.

When the fittings are positioned on the car as shown in Fig. 5 the car floor 15 fits over the plate 25 and may be suitably cut 100 away to clear the spacer block 27. The compartments are adapted to rest directly on this floor. They are each bound on the vertical edges by suitable reinforcing angle bars 39 as shown in Figs. 1, 2, 3 and 5. These 105 angle bars may turn in slightly at the very bottoms as shown at 40 to assist in guiding the compartments into position on the car.

Referring to Figure 3, it will be seen that each combined stop and stake pocket fitting 110 provides two angular pockets 41 to accommodate the lower portions of the vertical edges of the adjacent compartments as clearly shown. A material clearance space 115 appears in Figure 3 between the reinforcing angles and the pocket walls which is to insure proper fit without binding for all compartments. It will be seen that the spacer block 27 prevents any material fore and aft movement of the compartments and that the 120 wings 31 prevent lateral movement of the compartments because each compartment will really be engaged by four of the fittings. The sloping walls 28 and 28' at the top of the spacer block assist in positioning the 125 compartments in a fore and aft direction when they are dropped into position on the car and the sloping parts 32 of the wings 31 perform the same function in a lateral direction.

It will be seen that a car, provided with ordinary stake pockets, and with some stake pockets constructed according to the present invention, can be used either for holding 5 freight compartments or can, without any change, be used as an ordinary flat car being adapted to receive substantially the normal number of stakes in the customary manner. It has not been found necessary to provide 10 any further means of attaching the compartments to the car other than setting them on the floor thereof in the pockets provided by the stop members. The weight of the compartments will prevent them from upsetting 15 and they are prevented from sliding laterally or longitudinally by engagement with the stop members as explained.

Having thus described the invention, what is claimed as new and desired to be secured 20 by Letters Patent is:

1. The combination with a railway flat car and removable freight containers mounted thereon, of castings secured to the side sills of the car and each engaging the adjacent 25 corners of two of said compartments, and a collar forming a stake pocket integral with each casting between the planes of the portions thereof engaging the sides of the containers and extending out beyond said sills.
2. The combination with a flat car, and a removable freight container mounted thereon, of a casting secured to the car at the side thereof, said casting engaging a side 30 wall of said container to position the same, and a collar forming a stake pocket integral with said casting.

3. The combination with a flat car and a removable freight container mounted thereon, of a casting secured to a side sill of the 40 car and engaging two adjacent side walls of said container to position the same and a collar forming a stake pocket integral with said casting and lying in the angle formed by the extensions of the planes of said side 45 walls.

4. The combination with a flat car and removable freight containers mounted thereon, of a casting having a plate secured to a side sill of the car, a part on said casting 50 engaging the lateral facing walls of two adjacent containers, means on said casting to engage a longitudinal wall of each of said adjacent containers, a pair of spaced webs bracing said means from said plate, and 55 means connecting said webs to form with them and the plate a stake pocket.

5. As an article of manufacture, a fitting for flat cars including a plate adapted to be secured against the vertical face of a side 60 sill of a car, a plate adapted to rest on the top of said sill, a spacing block extending from said second plate, wings extending from said block and meeting the junction of said plates, webs secured to the junctions 65 of said wings and block and to said first

mentioned plate, and a connecting member joining a portion of the free edges of said webs to form a stake pocket.

6. The combination with a flat car and a plurality of independent freight compartments mounted thereon, of a casting secured to a side sill of the car and projecting above the floor thereof, a spacer block on said casting extending inwardly between two adjacent compartments, wings extending from 70 said block to form therewith pockets to receive the lower corners of said compartments and means extending from said block beyond said sill to form a stake pocket.

7. As an article of manufacture, a fitting 80 for flat cars including a plate adapted to be secured against the vertical face of a side sill of the car, a spacing block having its outer wall substantially coextensive with said plate, wings extending from the outer 85 wall of said block and substantially coextensive therewith and with said plate, the upper surfaces of said block sloping toward the front and rear of the car and the upper parts of said wings sloping upwardly and 90 away from the car.

8. The combination of a flat car and a pair of independent freight containers thereon, of means secured to said car to freely receive the lower corners of said containers 95 to space and retain the same on the car and a loop on said means laterally of said space to form a stake pocket.

9. In a flat car, in combination, side sills, 100 stake pocket fittings secured to said sills, certain pockets on each sill extending above the floor of the car and each such fitting having means thereon to engage with the corners of two adjacent, independent, removable freight containers arranged on said 105 car to space them respectively fore and aft of said pocket.

10. The combination with a flat car and a plurality of independently removable freight containers adapted to be mounted 110 thereon extending from side to side of the car and each having a door facing a side of the car, of a plurality of stake pocket fittings secured to each side sill of the car, those intermediate the ends of the individual compartments being below the level of the car floor and those at the ends of said compartments extending above the car floor to engage with said compartments.

11. The combination with a flat car and 120 a plurality of independently removable freight containers adapted to be mounted thereon extending from side to side of the car and each having a door facing a side of the car, of a plurality of stake pocket fittings secured to each side sill of the car, those intermediate the ends of the individual compartments being below the level of the compartment door bottoms and those 125 fittings at the contiguous ends of said compartments.

partments extending upwardly and inwardly to form two pockets on each fitting for the corners of said compartments.

12. As an article of manufacture, a fitting for flat cars including a plate adapted to be secured against the vertical face of a side sill of the car, a spacing block secured to said plate and adapted to extend over said sill and a stake pocket loop on the opposite side 10 of said plate and in alignment with said block.

13. As an article of manufacture, a fitting for flat cars including a plate adapted to be secured against the vertical face of a side sill of the car, a spacing block secured to 15 the inner face of said plate above said sill, a stake pocket loop on said plate opposite said block and common bracing members for said loop and block.

In testimony whereof I hereunto affix my signature.

WILLIAM F. KIESEL, JR.
